UNITED STATES PATENT OFFICE.

CECIL E. CLIPPINGER AND JOHN A. SMITH, OF CARMI, ILLINOIS.

ADJUSTABLE PRINTER'S CHASE.

1,105,758.

Specification of Letters Patent.

Patented Aug. 4, 1914.

Application filed September 22, 1913. Serial No. 791,196.

To all whom it may concern:

Be it known that we, CECIL E. CLIPPINGER and JOHN A. SMITH, citizens of the United States of America, residing at Carmi, in the county of White and State of Illinois, have invented certain new and useful Improvements in Adjustable Printers' Chases, of which the following is a specification, reference being had therein to the accompanying drawing.

This invention relates to a printer's chase, and the principal object of the invention is to provide a chase with a plurality of bars which are so mounted that they may be moved so that a block of type may be held tightly in position.

Another object of the invention is to provide an improved means for adjustably holding the bars in place.

Another object of the invention is to so construct the bars that they may be given an additional tightening movement after they have been moved toward the block of type as far as the ratchet will permit.

This invention is illustrated in the accompanying drawings, wherein:

Figure 1 is a plan view of the chase. Fig. 2 is a longitudinal sectional view taken along the line 2—2, of Fig. 1. Fig. 3 is a fragmentary sectional view of one corner of the chase. Fig. 4 is a sectional view taken along the line 4—4, in Fig. 3. Fig. 5 is a sectional view taken along the line 5—5, in Fig. 3. Fig. 6 is a perspective view of one of the pawl carrying heads which are carried by the sliding arms. Fig. 7 is a perspective view of the pawl shown in Fig. 6. Fig. 8 is a perspective view of one of the cams which are used for giving the bars an additional tightening movement. Fig. 9 is a perspective view of the key which is used for turning the cam shown in Fig. 8. Fig. 10 is a fragmentary sectional view taken along the line 10—10 of Fig. 1.

This chase has a rectangular frame 10 which is made up of a plurality of strips as shown in Fig. 10. It should be noted that the strips forming the longitudinal bars of the frame are beveled as shown in Figs. 1 and 10 so that when the chase is put in the press the press may close easily without the chase getting in the way. The strips 11 which are used in forming the bars of the frame extend beyond the upper and lower strips 12 and the intermediate strip 13 is cut to form teeth 14, thus forming a toothed

rack between the strips 11. The protruding inner edge portions of the strips 11 are provided to constitute guiding means for the bars which are slidably connected with the frame.

The longitudinally-extending bars 15 are mounted in the frame and each is provided with a longitudinally-extending pocket 16 in which there is mounted an auxiliary strip 17. A head 18 is carried at each end of each of the strips 17 and extends to one side of the bar so that there is provided a pocket in which a pawl 19 is pivotally mounted. These pawls 19 engage the teeth 14, as shown in Fig. 3, and are yieldably held in engagement with the teeth by the springs 20. This construction permits the bars 15 to be moved toward each other and held in adjusted position so that the block of type which is placed between the bars will be tightly clamped.

The strips 17 carry heads 18 which are positioned in alinement with the heads 21 and are provided with cut-out portions registering with cut-out portions formed in the heads 21 and forming pockets 22 in which the cams 23 are rotatably mounted. The springs 24 normally hold the strips 17 in the grooves 16, but when the cams 23 are turned by the key 25, the strips 17 will be forced out of the grooves 16 against the tension of the springs 24 so that the block of type may be securely clamped in case the bars 15 do not tightly grip the block of type when moved toward the same as far as permitted by the pawls.

The transversely-extending bars comprise the major and auxiliary members 26 and 27, each of which is composed of the upper and lower strips 28 and 29 held in spaced relation, so that the longitudinally-extending bars can pass through the transversely-extending bars. Each of the major members carries a head 30 similar to the head 18, a pawl 31 being pivotally connected with each of the heads 30 so that the pawls may engage the teeth 14 and hold the transversely-extending bars in an adjusted position.

The auxiliary members 27 are provided with heads 32 which are provided with cut-out portions registering with cut-out portions formed in the heads 30 and form pockets in which cams 33 are mounted.

The major and auxiliary members are held in the position shown in Fig. 3 by the springs 34 so that the transversely-extend-

ing bars may be tightened in the same manner that the longitudinally-extending bars are.

When using this chase, the block of type is put in the center of the chase between the transversely and longitudinally-extending bars. The transversely and longitudinally-extending bars are then moved toward the center of the chase until they are brought into engagement with the block of type. The pawls will hold the clamping bars in engagement with the block of type so that the type will be prevented from dropping out of the chase when the chase is lifted and placed in the press. If the bars do not clamp the type with sufficient tightness, the cams 33 can be rotated to bring the auxiliary strips into tight engagement with the type. When the chase is removed from the press, the cams are returned to the normal position and the pawls are then pressed out of engagement with the teeth 14 and the clamping bars moved to release the block of type.

A scale shown in Fig. 1 is provided so that the bars may be properly adjusted in order to bring the block of type in the center of the chase or in any other portion of the chase where it is desired to have the type located. This scale makes it very easy to properly locate the type.

A chase has, therefore, been provided in which the block of type may be quickly clamped in the desired position, and in which the clamping bars may be quickly and easily moved to grip the type and release the same as desired.

What is claimed is:

1. A chase comprising a frame having the inner faces of its side bars provided with teeth, clamping bars slidably mounted in said frame, each of said clamping bars

comprising a major strip and an auxiliary strip, heads carried by said major and auxiliary strips and provided with cut-out 45 portions positioned in alinement and forming pockets, resilient means yieldably holding said major and auxiliary strips in close engagement, cams mounted in said pockets whereby said auxiliary strips may be moved 50 away from said major strips, and pawls engaging the teeth of said frame whereby said bars may be held in an adjusted position.

2. A chase comprising a frame having the inner faces of its side bars provided with teeth, clamping bars slidably mounted in said frame, each of said clamping bars comprising a major strip and an auxiliary strip, heads carried by said major and auxiliary strips and provided with cut-out portions positioned in alinement and forming pockets, resilient means yieldably holding said major and auxiliary strips in close engagement, cams mounted in said pockets whereby said auxiliary strips may be moved 60 away from said major strips, the heads carried by said auxiliary strips extending beyond the side portions of said strips and provided with secondary pockets, spring-actuated pawls carried within said last mentioned pockets engaging the teeth of said frame whereby said bars may be held in an 65 adjusted position, said pawls being carried adjacent said cams for receiving the direct pressure imparted by the rotation of said 70 cams thereby holding said bars more firmly.

In testimony whereof we hereunto affix our signatures in presence of two witnesses.

CECIL E. CLIPPINGER.
JOHN A. SMITH.
